UNITED STATES PATENT OFFICE.

THOMAS H. JONES, OF ALBIA, IOWA.

TOP FOR VEHICLES.

1,407,198.

Specification of Letters Patent. Patented Feb. 21, 1922.

Application filed September 28, 1920. Serial No. 413,284.

To all whom it may concern:

Be it known that I, THOMAS H. JONES, a citizen of the United States, residing at Albia, in the county of Monroe and State of Iowa, have invented certain new and useful Improvements in Tops for Vehicles, of which the following is a specification.

This invention relates to tops for vehicles, especially motor vehicles, the primary object of which is to combine the salient advantages of a sedan and open touring car, at the same time greatly reducing the weight of the present day sedan, as well as curtailing the cost of manufacture and likewise giving the same protection to the occupants of the vehicle, but eliminating the undesirable side curtains used on touring cars.

A coordinate object of the invention is to equip the top with slidable sashes which may be opened to permit ingress of air and which may be folded into the top when not in use.

A further object is provide a top having sliding sashes which can be adjusted so as to capacitate as sun shades for the protection of the occupants of the vehicle.

The above and other objects of this invention will be in part described and in part understood from the following description of the present preferred embodiment of the invention taken in connection with the accompanying drawings, wherein:

Fig. 1, is a side elevational view of a top constructed in accordance with my invention and showing the sashes closed.

Fig. 2, is a similar view showing the sashes in open position.

Fig. 3, is a transverse sectional view of the device showing one sash in adjusted position, and acting as a sun shade, and the other sash folded completely in the top of the vehicle.

Fig. 4, is a detail fragmentary sectional view of the device.

Fig. 5, is a perspective view of one of the sash frames or skeleton, and

Fig. 6, is a perspective view of one of the complete sashes.

In the drawings, in order to illustrate the application of this invention, a portion of a vehicle body 7 is shown, which may be of the usual or any desired configuration. The body has preferably upstanding therefrom a plurality of posts 8, which may be formed integral with the body or detachably associated therewith as found expedient. A

rear end portion 9 is provided which is equipped with a transparent panel 10 on each side. The front of the body has the usual wind shield mounted thereon. 60

The top per se consists of an inner covering 11 made of any desirable fabric, and an outer covering 12 made of leather, mohair, or other suitable material. The inner and outer coverings are spaced to provide a compartment 13 which is relatively wide at the lateral margins thereof and gradually tapers toward the center. Bracing struts 14 extend longitudinally through the compartment 13 and are engaged with the covering 11 to support the latter. Transversely extending struts are provided to support the outer covering 12, in a well known manner, these struts being indicated by the dotted lines 15 in Fig. 12 of the drawings. It will 75 be observed that the outer covering 12 gradually tapers towards the forward end of the car for purposes hereinafter set forth.

Each sash consists of a main rectangular frame generally designated 16 and consisting of two elongated straps 17, one end of each of which is rounded and bent into an arcuate configuration to provide feet 18, which freely slide against the inner face of the outer top covering 12. Braces 19 are 85 engaged with said straps adjacent the ends of the latter. A circular rod 20 is engaged with the opposite ends of said straps 17 to those comprising the feet 18. Preferably these ends are engaged by convoluting the 90 strap terminals around said rod. Links 21 extend outwardly from said rod 20 within the convoluted terminals of said straps 17. The free ends of the links 21 are pivotally mounted upon guide plates 22 which are 95 carried on the proximate faces of the posts 8. The straps 17 are preferably made of an inherently resilient material, such, for instance, as spring steel, and are wrapped with leather or the like to give a finished appearance to the sash. Window panes are mounted in each of the sashes and are preferably of a two-part construction. The lower part, as indicated at 23, is preferably

made of an opaque material, such as dark 105 green celluloid, while the upper part 24 is made of a transparent material, preferably a plain celluloid, in view of the flexibility of the latter. Flaps 25 are mounted upon the lower ends of the sashes so as to overlap the 110 jointure of the top with the vehicle body to prevent the seepage of water, ingress of air,

or the like. This flap is preferably made of leather and is equipped with a handle 26 by which the sash is conveniently operated.

In order to facilitate movement of the 5 sashes into the compartment 13, a series of rollers 27 are provided, one being cooperable with each sash. Each roller is mounted in a pair of suitable brackets 28, the latter in turn being detachably secured to the 10 posts 8 through the medium of set screws 29, or the like. As will be apparent, upward pressure on the handle 26 will cause the sash to be moved across the rollers 27 and into the compartment 13, in superimposed relation to the struts 14. The inherent 15 flexibility of the sashes will permit their movement into the compartment 13 without difficulty. In swinging into the compartment the sash will travel through the arc of 20 a circle as indicated by the dotted line in Fig. 3 of the drawings. When completely folded in compartment 13 the links 21 will lie snugly in engagement with the plates 22.

The sashes are adapted for use also as 25 sun shades to protect the occupants of the vehicle from the rays of the sun. When it is desired to use the sashes in this way, they are moved upwardly to the position shown on the left side of Fig. 3 of the drawing, and 30 held in this position by means of a small link 30. One end of said link is pivoted on the guide plate 22 while the opposite end is provided with a stud 31, which engages a corresponding opening 32 in the link 21. 35 Although one link 30 only has been described, it is nevertheless to be understood that a pair of these links may be used with each sash if found expedient. When adjusted to the position shown in Fig. 3, it 40 will be apparent that the transparent portion 24 of the sash will lie in the compartment 13, while the opaque portion 23 thereof depends at an angle from the top 12, so as to lie directly in the path of the sun 45 ray on either side of the vehicle.

From the above it is apparent that the sashes may be expeditiously opened or closed

from either the outside or inside of the vehicle. Their flexibility and lightness makes it possible for them to be conveniently stored in the compartment 13 without in any way mutilating the vehicle top. Moreover, the compartment 13 will serve as an air chamber with obvious beneficial results. By tapering the top covering 12 55 downwardly, a minimum resistance will be offered during travel of the vehicle.

Various changes may be made in the details of construction, proportion and arrangement of parts within the scope of the 60 appended claims.

What is claimed is:

1. A top for vehicles including a sash equipped with a lower opaque pane and an upper transparent pane, the latter of which lies in the path of vision of the vehicle occupants when the sash is in a vertical position, said sash being slidable into the vehicle top to dispose the transparent pane therein and to retain the opaque pane at an inclination from the top of the vehicle to capacitate as a sun shade for the occupants of the vehicle, and links carried by each sash and engageable with the vehicle body to hold the sash in a predetermined position of adjustment.

2. An attachment for vehicles including a top provided with a compartment, sashes slidable in said compartment each of which is equipped with superimposed transparent and opaque panes said transparent pane being usable when the sash is in a vertical position, independent means for each sash to permit use of the opaque pane only, and feet formed on the upper ends of the sides 85 of each sash for facilitating insertion and removal of the sashes in and from said compartment respectively.

In testimony whereof I affix signature in presence of two witnesses.

THOMAS H. JONES.
